UNITED STATES PATENT OFFICE.

EARL H. DUKE, OF HOUSTON, TEXAS, ASSIGNOR OF ONE-HALF TO RUDOLPH P. SUHM,
OF HARRIS COUNTY, TEXAS.

ICE HOLDER.

Application filed December 16, 1921. Serial No. 522,839.

To all whom it may concern:

Be it known that I, EARL H. DUKE, citizen of the United States, residing at Houston, in the county of Harris and State of Texas, have invented certain new and useful Improvement in an Ice Holder, of which the following is a specification.

This invention relates to new and useful improvements in an ice holder.

- 10 One object of the invention is to provide a device of the character described specially designed for application to the running board of a motor vehicle and provided for the purpose of holding a block of ice thereon.
- 15 Another object of the invention is to provide an attachment of the character described which is of simple construction and may be readily applied to and detached from a motor vehicle running board and which 20 will securely hold a block of ice placed on said running board.

Another object of the invention is to provide an efficient device of the character described which at the same time is of such a 25 simple character that it may be very cheaply manufactured.

With the above and other objects in view the invention has particular relation to certain novel features of construction, arrangement of parts and use, an example of which is given in this specification and illustrated in the accompanying drawings, wherein:—

Figure 1 is a plan view of the attachment.

Figure 2 is an edge view thereof and

35 Figure 3 shows the device applied to a vehicle running board.

Referring now more particularly to the drawings, the numeral 1 designates the running board of a motor vehicle.

40 The numeral 2 designates a thin metal strap whose outer end is formed with a U-shaped clamp 3 said strap resting upon the upper side of the running board in a trans-

verse position and said clamp embracing the outer edge of said running board. The strap 45 is secured in place by means of a clamp screw 4 which is threaded through the under-turned end thereof and which clamps against the under side of the running board.

Thrown up from the material of the strap 50 are the end teeth 5, 5 which are preferably inclined upwardly, and also intermediate teeth 6, 6 which are inclined from the vertical.

The block of ice to be carried is set on the holder and the teeth 5, and 6 bite into the 55 under side thereof. The teeth 5 will hold the block against lateral slippage, in either direction and the teeth 6 will hold it against endwise slippage.

Ice may be thus conveniently carried about 60 on the running board without the danger of slipping off or marring the side of the vehicle.

What I claim is:

An ice holder including a single strap 65 whose outer end is overturned and formed into a U-shaped clamp which receives the outer edge of a vehicle running board, a clamp screw threaded through the overturned end of said clamp and engaging with 70 said running board, and holding the strap closely against the upper side of said running board, end teeth extending upwardly from said strap and inclined in opposite directions, and intermediate side teeth 75 standing from said strap and inclined in opposite directions, said teeth being triangular and thrown up from the material of the strap and being in staggered relation.

In testimony whereof I have signed my 80 name to this specification in the presence of two subscribing witnesses.

EARL H. DUKE.

Witnesses:

E. V. HARDWAY,
L. M. HOCK.
